UNITED STATES PATENT OFFICE.

ALEXANDER HAMILTON CAMPBELL, OF WOODMERE, NEW YORK.

HAND-TRUCK.

1,140,785.

Specification of Letters Patent. Patented May 25, 1915.

Application filed September 1, 1914. Serial No. 259,596.

To all whom it may concern:

Be it known that I, ALEXANDER HAMILTON CAMPBELL, a citizen of the United States, residing at Woodmere, in the county of Nassau, State of New York, have invented certain new and useful Improvements in Hand-Trucks, of which the following is a clear, full, and exact description.

This invention relates to an improvement 10 in hand trucks or similar devices designed for the transportation of goods.

The object of this invention is to provide a cradle to be attached to hand trucks, skids or the like that will act to protect the edges 15 of comparatively soft material, such as paper, as well as to facilitate the loading or the placing of the same upon the trucks.

Paper, when rolled in large masses, such as are supplied to printing houses, for instance, is very heavy and bulky to handle and it frequently happens that the lower edge of these rolls of paper becomes crushed or damaged by reason of the fact that the 20 said rolls of paper are allowed to rest, at 25 times, upon said lower edge. When a roll of this paper is to be placed upon a hand truck it will be tilted and will rest for a time upon its lower edge. This happens when the rolls are taken from a truck or express 30 wagon at which time the rolls are frequently allowed to strike upon this lower edge when they are pushed out of the truck.

My improved device is designed to protect the edge of the above mentioned rolls of 35 paper and prevent the said edge from being injured by contact with the ground.

In the drawing, which forms part of this specification, Figure 1 is a diagrammatic view illustrating a hand truck having applied thereto my improved attachment; Fig. 2 is an enlarged fragmentary sectional view illustrating a roll of paper upon a hand truck and also the manner in which my improvement cradles the end of the roll; Fig. 3 is a top plan view of the forward end of a hand truck, and also of my improved attachment; Fig. 4 is an enlarged detail view illustrating the fastening or locking means which forms a part of my invention; Fig. 5 is a cross-sectional view on a reduced scale, the section being taken on a line 5-5 in Fig. 2.

My invention consists of a cradle or support 1 designed for attachment to a hand truck 2 or a skid. The cradle 1 or support consists of a table portion 3 and a flange por-

tion 4 located preferably at a right angle to the table portion, the said table portion being provided with a lug 5 by which means the cradle is pivotally secured, by a pin 6, to the side rails 7 of the truck.

As will be seen in Fig. 5, the lug 5 is somewhat narrower than the table portion 3, and fits between the rails 7, whereby shoulders 8 are provided upon which the cradle will rest when the truck is loaded, as shown in Fig. 2, whereby further downward movement of the cradle will be prevented. To lock the cradle in loaded position, I employ a latch 9 pivotally secured to the table 3 of the cradle 1 as at 10, a fulcrum-block 11 being provided for the purpose. The latch 9 has only enough pivotal movement to permit it to engage a keeper, in this instance the axle 12 of the truck. As shown in Fig. 5 I preferably curve the table 3 to more completely cradle the roll of paper or other circular or cylindrical object carried by the truck.

To prevent the edge 13 of the roll 14 from coming in contact with the ground when loading or unloading, I provide the cradle with a pocket or recess 15, the sides 16 of the pocket being angularly disposed relatively to the adjacent surfaces of the 35 table and flange of the cradle, whereby the bottom 17 of the pocket is located beyond the line of either of the adjacent surfaces of the said table or flange, to an extent sufficient to prevent the edge 13 of the roll from coming 90 in contact therewith.

To facilitate the tipping of the roll 14 and truck after the roll has been secured thereto in a manner to be described, I provide the cradle 1 with a projection or fulcrum point 95 18, the function of which will be herein-after set forth.

The operation of the device will now be described.

When a roll of paper such as 14 is to be 100 moved, the truck 1 will be rolled up and the edge 19 of the flange 4 will be inserted under the roll as shown in Fig. 1, the latch 9 having first been released from the axle 12. Before the flange has been inserted the roll 105 14 may be tilted slightly ahead after which the truck will be rolled ahead until the table 3 contacts with the roll. After the table has contacted with the roll, the truck 1 will be swung upwardly in the direction of the arrow 20, Fig. 1, until the support 21 on the truck touches the roll, at which time the

latch 9 will engage the axle 12. This operation will cause the wheels 22 of the truck to leave the ground. The flange 4 will now support the entire mass. After the truck has 5 been brought up to the roll a strap or other fastening element can be used to secure the truck and roll together at their upper ends. To cause the wheels 22 to again come in contact with the ground the truck will be 10 pulled in the direction of the arrow 23, Fig. 1, which action will also cause the roll 14 to tip. As these rolls of paper are heavy, I prefer to employ some means to facilitate the tipping thereof and such 15 is the function of the projection or fulcrum point 18.

It will be seen by referring to Fig. 1 that the surface 24 of the projection 18 is rounded. Hence when the truck is pulled 20 back the roll will be gradually tipped, the truck acting as a lever. At about the time that the tip of the fulcrum 18 touches the ground the wheels 22 will contact with the ground, and the mass will be in the position shown in Fig. 2, or ready for transportation.

When the truck is to be unloaded a reversal of the above operation will be gone through. At no time during loading or unloading will the edge 13 of the roll 14 come 30 in contact with the ground.

What I claim is:

1. In combination with a transporting device, a supporting cradle pivotally secured 25 thereto at one end thereof, said cradle consisting of a table portion and a flange located at a right angle thereto, said cradle being provided with a recess or pocket to receive the edge of the article to be trans-

ported and keep same out of contact with 40 said cradle, and releasable means to lock said cradle against pivotal movement.

2. In combination with a transporting device, a supporting cradle pivotally secured thereto, said cradle consisting of a table 45 portion and a flange located at an angle thereto, said cradle being provided with a pocket or recess, the bottom of said pocket or recess being out of alinement with the adjacent surfaces of said table and flange, 50 a latch, carried by said cradle, and a keeper carried by the transporting device adapted to engage said latch.

3. In combination with a transporting device, a supporting cradle pivotally secured 55 thereto, said cradle consisting of a table portion and a flange located at an angle thereto, said cradle being provided with a pocket or recess, the bottom of said pocket or recess being out of alinement with the 60 adjacent surfaces of said table and flange, a latch carried by said cradle, and a projection or fulcrum point carried by said cradle projecting downwardly therefrom.

4. In combination with a transporting device, a supporting cradle pivotally secured thereto, means to lock said cradle against 65 movement and a projection or fulcrum point carried by said cradle projecting downwardly therefrom.

Signed at New York, N. Y., this 31st day of August, one thousand nine hundred fourteen.

ALEXANDER HAMILTON CAMPBELL.
